United States Patent Office

Des. 184,806
Patented Apr. 7, 1959

184,806

VISOR FOR SPECTACLES OR SIMILAR ARTICLE

Robert P. Evans, Westwood, Mass.

Application March 24, 1958, Serial No. 50,160

Term of patent 7 years

(Cl. D57—1)

Fig. 5.

Fig. 1 is a top plan view,
Fig. 2 is a front elevational view,
Fig. 3 is a rear elevational view,
Fig. 4 is a bottom plan view, and
Fig. 5 is an end elevational view of a visor for spectacles, embodying my new design.

I claim:

The ornamental design for a visor for spectacles, or similar article, substantially as shown.
